UNITED STATES PATENT OFFICE.

LOUIS R. RUSSELL, OF MARION, OHIO, ASSIGNOR TO THE MARION STEAM SHOVEL COMPANY, OF MARION, OHIO, A CORPORATION OF OHIO.

EXCAVATING MECHANISM.

Application filed May 25, 1925. Serial No. 32,637.

This invention relates to excavating mechanism and more particularly to a boom designed for use with excavating mechanism in tunnels or other locations where the overhead clearance is limited.

Excavating machinery of this character ordinarily employs a straight boom and the excavating dipper is supported on that boom between its ends. In order that the dipper 10 may be elevated to the top of the tunnel, that is, to a height substantially even with the point of the boom, it is necessary to use a dipper handle of sufficient length to enable the dipper to be projected beyond the 15 point of the boom and when such a long dipper handle is used it is apt to be thrust into the overhead structure or against parts of the mechanism upon the return of the dipper to its initial position.

One object of the invention is to provide 20 an excavating mechanism comprising a boom so shaped that the dipper or other excavating device may be elevated to substantially the height of the point of the boom by the 25 use of a relatively short handle.

A further object of the invention is to provide a mechanism of this character with means for limiting the movement of the dipper toward the boom.

A further object of the invention is to provide 30 a boom of this character which will be simple in its construction, of a strong durable character and which can be manufactured at a relatively low cost.

Other objects of the invention will appear 35 as the device is described in detail.

In the accompanying drawings Fig. 1 is 40 a side elevation, partly broken away, of a portion of an excavating mechanism embodying my invention; Fig. 2 is a side elevation of the boom, partly broken away; Fig. 45 3 is a plan view of the connection between the dipper handle and the dipper, showing the boom in section; Fig. 4 is a detail view of the casting at the outer end of the dipper handle; and Fig. 5 is a plan view of the point of the boom and the sheaves carried thereby.

In these drawings I have illustrated one 50 embodiment of my invention and have shown the same in connection with a power shovel, the main features of construction of which

are well known. As here shown, the shovel 55 comprises a base 1 supported by suitable traction devices 2 and having mounted thereon a revolving platform 3 which carries the power plant and excavating mechanism. Mounted at one end of the revolving platform 60 is a boom 4 which is preferably pivotally mounted on the platform and extends forwardly and upwardly therefrom. The boom may be supported at the desired height in any suitable manner, as by means of cables 5. Supported from the boom, between the 65 ends thereof, is an excavating dipper 6 which is carried by a handle 7. The boom preferably follows the standard construction in which the boom comprises two parallel members rigidly connected one to the other but spaced apart for a portion of their length 70 to provide an opening or slot through which the dipper handle extends. The dipper handle is provided on its lower edge with rack teeth 8 which mesh with a pinion 9 carried by a shaft 10 journaled in suitable bearings on the two members of the boom and connected by means of a train of gears 11 with a

motor, such as the electric motor 12 here shown. The operation of the pinion 9 by the motor imparts lengthwise movement to the dipper handle to move the dipper toward and from the boom and to crowd the dipper 75 into the bank. Upward movement is imparted to the dipper by means of a cable 13 which, in the arrangement here shown, is fixed at one end to a lug 14 carried by the dipper and extends about one of two sheaves 15 at the point of the boom, then about a sheave 16 connected with the dipper and then about a second sheave 15 at the point of the 80 boom and rearwardly to a drum 17 on the platform 3. Ordinarily the boom 4 is substantially straight, that is, it extends in a straight line, but in order to secure the desired elevation of the dipper with a short 85 dipper handle I have arranged the front and rear portions 18 and 19, respectively, of the boom in intersecting lines, with the front portion extending upwardly from the line of the rear portion. In the present construction, both the front portion and the rear portion are substantially straight and have 90 their adjacent ends rigidly connected one to the other by means of a curved portion 20,

95

100

the curvature of which is such as to support the front portion 18 at the desired angle to the length of the rear portion 19. The boom comprises an integral structure, the several portions thereof being rigidly connected one to the other, or fabricated. The dipper handle 8 is mounted on the boom at a point near the adjacent ends of the front and rear portions thereof and, in the present instance, 10 the pinion 9 is arranged close to the forward end of the rear portion 19 of the boom, thus enabling the handle and the dipper to be swung rearwardly or forwardly into the several positions shown in Fig. 1, about a relatively short radius. It will be noted that 15 the dipper may be moved to a position in front of but substantially at the same height as the point of the boom, which ordinarily extends close to the overhead structure of 20 the tunnel in which the machine is working, and when in this position it projects but a short distance from the point of connection of the handle with the boom, thus enabling a very short handle to be employed. Consequently 25 when the handle is retracted and the dipper moved toward the boom the handle will not project beyond the boom far enough to come in contact with the sheaves 15, motor 12 or other parts of the mechanism, or with the overhead structure of the tunnel. The dipper arm has, however, ample length to enable the dipper to be moved to all necessary positions, as shown in Fig. 30 1. If desired, means may be provided to limit the movement of the dipper toward the boom and, in the present device, the castings 21, by means of which the dipper handle is connected with the dipper, are provided with shoulders, here shown as flanges 22, on the opposite sides thereof and arranged to engage the adjacent edges of the two boom members and thus provide a positive stop for the dipper and to limit the rearward movement of the dipper handle. These shoulders 35 are so arranged as to provide a substantially flat contact between the same and the respective boom members in all positions of the dipper with relation to the boom. In order that the dipper may be drawn close to the 40 point of the boom the sheave 16 is arranged close to the rear wall or back of the dipper and is here shown as mounted between bearing lugs 23 carried by the dipper back, and the castings 21 of the handle are spaced apart 45 to provide a recess or slot 24 into which the sheave extends. The two parts or castings 21 are connected one to the other by a bottom plate or casting 25, which is also connected to the dipper. 50 While I have shown and described one embodiment of my invention I wish it to be understood that I do not desire to be limited to the details thereof as various modifications may occur to a person skilled in the 55 art.

Having now fully described my invention, what I claim as new and desire to secure by Letters Patent, is:

1. In a boom for a mechanism of the character described, comprising a rear portion adapted to be connected with a supporting structure, a forward portion extending upwardly with relation to said rear portion, and means for mounting a dipper handle on said boom with its fulcrum point 75 above the rear portion thereof and near the adjacent ends of the two portions thereof.

2. A boom having an intermediate portion curved about a horizontal axis and arranged to support the forward portion of the boom 80 at an angle to the rear portion thereof, and means for mounting a dipper handle on said boom with its fulcrum point adjacent to the upper edge of the rear portion thereof and close to said curved portion thereof.

3. In a structure of the character described, a boom comprising front and rear portions having their adjacent ends rigidly connected one to the other and so arranged that the front portion will extend upwardly 90 at an angle to the rear portion, a pinion supported by said boom on an axis above the rear portion thereof and near the adjacent ends of said front and rear portions, a dipper handle having teeth to engage said pinion, and a dipper carried by said handle.

4. In a structure of the character described, a boom comprising front and rear portions having their adjacent ends rigidly connected one to the other and so arranged 100 that the front portion will extend upwardly at an angle to the rear portion, a dipper handle, means for pivotally mounting said dipper handle on said boom with its fulcrum point above the rear portion thereof and 105 near the adjacent ends of the two portions thereof, a dipper carried by said handle, and a stop carried by said dipper handle to engage the adjacent edge of said boom and limit the rearward movement of said dipper 110 handle with relation to said boom.

5. In a structure of the character described, a boom comprising front and rear portions having their adjacent ends rigidly connected one to the other and so arranged 115 that said front portion will extend upwardly at an angle to said rear portion, a dipper handle mounted on said boom near the adjacent ends of the two portions thereof for swinging movement, a casting carried by the forward end of said dipper handle and having a recess in the forward portion thereof, and lugs carried by said dipper adjacent to said casting, a sheave mounted between said lugs and extending into the recess in said casting, a sheave mounted at the point of said boom, and a cable to connect the sheave of said dipper with the sheave of said boom.

6. In a structure of the character described, a boom comprising front and rear 130

portions having their adjacent ends rigidly connected one to the other and so arranged that said front portion will extend upwardly at an angle from said rear portion, a dipper handle mounted on said boom near the adjacent ends of said portions thereof for both swinging movement and longitudinal movement, a casting secured to the forward end

of said dipper arm, and a dipper secured to said casting, said casting having a portion arranged at the side of said dipper arm and constituting a shoulder to engage the adjacent edge of said boom. ¹⁰

In testimony whereof, I affix my signature hereto.

LOUIS R. RUSSELL.
